UNITED STATES PATENT OFFICE.

JAMES WAYLAND, OF NEWARK, NEW JERSEY.

LINT-MACHINE.

SPECIFICATION forming part of Letters Patent No. 417,613, dated December 17, 1889.

Application filed October 22, 1888. Serial No. 288,823. (No model.)

To all whom it may concern:

Be it known that I, JAMES WAYLAND, a citizen of the United States, residing at Newark, in the county of Essex and State of New Jersey, have invented certain new and useful Improvements in Lint-Machines; and I do hereby declare the following to be a full, clear, and exact description of the invention, such as will enable others skilled in the art to which it applies to make and use the same, reference being had to the accompanying drawings, and to letters and figures of reference marked thereon, which form a part of this specification.

This invention relates to that class of lint-machines in which the lint is formed by scraping the surface of a linen or cotton cloth, so that the fabric is partly disorganized or the texture is changed, so that a pile of loose fiber is raised from the warp and weft, and the cloth, while not entirely disintegrated, is sufficiently so to allow of the newly-formed lint fabric being easily torn.

The object of the invention is to prevent or greatly lessen the noise which has been produced in operating the prior devices; to obtain a more perfect lint fabric and increase the output of the same with a given expenditure of power; to reduce the cost of construction and limit the cost of repair; to secure a lighter machine, and one in which the wear can easily be taken up and the linting-knife can be adjusted to obtain any desired depth of lint.

The invention consists in the improved linting-machine and in the arrangements and combinations of parts substantially as will be hereinafter set forth, and finally embodied in the clauses of the claims.

Referring to the accompanying drawings, in which like letters and figures of reference indicate corresponding parts in each of the several figures, Figure 1 is a side elevation of the improved machine. Fig. 2 is a side view of mechanism adapted to operate the feed-roll. Figs. 3 and 4 are views of an arm carried by a rock-shaft and co-operating with an arm shown in Fig. 2 in supporting said feed-roll, part of said roll being also shown. Fig. 5 is a plan of the machine. Fig. 6 is a section on line z , showing the linting-tube and one of its bearings. Fig. 7 is a section of the

same and the linting knife or blade, taken on line x , Fig. 5. Fig. 8 is a section of the tension device, taken on line y , Fig. 5. Fig. 9 is a plan of a part of the tube and an end piece therefor for co-operating with the linting-blade and said tube, and Fig. 10 is a view of a set-screw for holding said tube in place. Fig. 11 is a broken side view, enlarged, and more clearly showing the mechanism for feeding and linting the cloth; and Fig. 12 is an edge view or section showing more clearly the relation of the linting knife or blade to the co-operating parts.

In said drawings, a indicates a suitable bed or frame provided with a suitable roll or holder b for the unlinted cloth, a tension device c , by means of which the passage of the cloth to the linting mechanism is retarded, so that said cloth will be presented to said linting mechanism under considerable tension, feed mechanism by means of which the cloth is caused to travel toward the linting mechanism, and said linting mechanism. In part 75 the said linting mechanism consists, preferably, of a tube d , adjustably held in end bearings e by set screws e' , which said end bearings are adjustably held upon the frame a by set-screws e'' , arranged in slot e^3 in any suitable manner. The tube may be adjusted in its bearings by hand, it being turned pivotally in one direction or the other and afterward held rigidly by the set-screw, as will be understood upon reference to Figs. 6 and 9. The 85 said tube d is longitudinally slotted, as at f , Figs. 9, 11, and 12, on the side toward the linting knife or blade, into which slot the edge of the said blade enters in the linting operation, as will be hereinafter described. 90

While I prefer a tube, inasmuch as it allows of a revolving adjustment, I may employ any other form in which two bearings $d' d'$ form the slot f , back of which is an opening or chamber d^2 , through which or into which the loose lint may pass and be removed or prevented from accumulating to such a degree as to interfere with the linting operation by producing a cushion or bed. The said linting-knife g is arranged on a rock-frame j , 100 having suitable bearings j' on the bed-frame, and allows of wear of the knife being taken up without interfering with the operation of the machine. By loosening the set-screw l' ,

by which the knife is held onto the frame, the said knife may be moved in or out by the hand to take up the wear or otherwise render the knife able to work more efficiently. The 5 linting-knife *g* is secured on said frame *j* on a seat *l*, adjacent to the slot *f* in the tube, so that as the frame rocks to and fro the linting edge enters and is withdrawn from said slot, as indicated in Fig. 12. The knife *g* is 10 caused to move toward said slot by suitable springs *m*, secured to projections or bearings *n* on the side of the rocking frame *j* opposite that on which the knife is seated, and to move in its opposite direction by a cam *J*, which 15 engages an arm or bearing *p* of the rocking frame *j*.

The cam *v* is arranged on a shaft *q*, Figs. 1, 5, and 11, and the latter is driven by a pulley *r* and has a fly-wheel *s*.

20 The fabric *B* to be linted travels between the linting knife or blade and the slotted tube, so that on the knife or blade entering the slot the cloth is forced out of its straight course and is brought into intimate contact 25 with the three bearings, two on the tube and one on the knife. By causing the cloth to be pulled backward while in this position over the edge of the blade or knife I produce a very perfect pile of loose fiber or lint on the 30 face of the cloth.

The mechanism I prefer to employ to draw the fabric over the knife when the latter is in the slot, as described, is illustrated more particularly in Figs. 1 and 11, in which *t* is a 35 rock-shaft journaled in the frame *a*, which shaft at or near its center carries a projection *u*, which engages a cam *o* on the cam-shaft *q*. At the ends of the shaft *t* are arranged feed-roll carriers or arms *w w'*, be- 40 tween which is disposed a feed-roll *2*, by means of which the cloth is fed forward to the linting mechanism. The reciprocating movement of the shaft *t* and arms *w w'* gives to the feed-roll a movement toward and from 45 the linting-blade and tube. The reciprocal movement of the feed-roll on the shaft *t* is so timed that when the linting-blade is withdrawn from the slot in the tube or between the bearings *d' d'* the feed-roll is moved

50 downward or toward said blade, thus allowing the fabric to drop through or between the linting parts. Then the linting-blade makes a return movement and forces the fabric into the tube, as indicated in Fig. 12. 55 The feed-roll is then forced or raised in a direction away from the linting-knife, so that the cloth is drawn over the edge of the blade, producing the pile of loose or partially-loosened fiber desired. The surface of the 60 feed-roll may be provided with any form of teeth commonly used in this class of machine adapted to prevent the cloth from slipping on the roll.

The spring *3*, Figs. 1 and 5, gives to the 65 feed-roll and its bearings a return motion after they have been acted on by the cam *v*.

The cloth *B* is fed forward slowly by a

mechanism arranged on the arm *w*. This consists of a gear *4*, arranged at the end of the feed-roll or feed-roll shaft *2*, which engages a worm-shaft *5*, having suitable bearings *6 6* on said arm *w* and carrying a worm-wheel *7*, which engages a ratcheted worm *8* on said arm. Said ratcheted worm engages a pawl *9*, carried on the frame *a* near the 70 shaft *t* and adjustable on said frame *a*, so as to vary the length of throw of the ratchet-wheel, the supports *93* for the pawl being fixed to the frame by a suitable set-screw *94*, passing through a slot *95* in the support, which 75 set-screw, being loosened, allows said support to be moved toward or from the ratchet-wheel, all as will be understood upon reference to Fig. 11. At each upward movement of the arm *w* the pawl causes the wheel *8* to make 80 a partial revolution, and this motion is transmitted to the feed-wheel and cloth by the gearing just described.

The tension device *c*, which I prefer to employ, consists of two parallel bars *c' c'*, held 85 apart and connected at their opposite ends by end pieces *c² c²*, Fig. 5, which provide center bearings *c⁴*, arranged in the frame *a*. The said tension device is held in any fixed position by a set-nut *c³*. By turning the frame 90 thus formed so that the cloth is given a very angular course I secure more or less tension—the greater the angle produced the greater the tension, as will be understood. The cloth is held in proper relative position in the tension device by guides *c⁵*, which are held on the bars *c' c'* by set-screws *c⁶*, and move laterally thereon, so as to enable them to be brought into proper relation to the cloth to 95 guide the same.

To increase the surface in engagement with the feed-roll, I have provided a bar *11*, which runs parallel with said feed-roll, beneath which the cloth is caused to pass before engaging the feed-roll, as indicated in 100 Fig. 1.

While I have thus specifically described the devices I employ in my operative machine, I do not wish to limit myself to the exact construction shown.

I am aware that various changes and equivalent constructions may be employed without departing from the spirit of the invention.

In operating the device the cloth passes from the roll *b* to and through the tension device to the feed-roll, where it is, while being slowly fed forward, given a reciprocating motion to and from the linting-blade. From the feed-roll the cloth passes between the linting-blade and the slotted tube, and from thence 120 to the floor or to a suitable receptacle provided to receive it.

It will be observed that the blade in its movement does not strike any cushion or co-operating-bed, as in prior devices, and as a 125 result I am enabled to secure more effective results without the noise and jarring incident to such a construction and operation, and as a further result the wear on the machine is 130

greatly reduced, and the machine may therefore be run at a much quicker speed, and thus turn out a larger quantity of work in a given time.

5 Having thus described the invention, what I claim as new is—

1. In a linting-machine, the combination, with a slotted tube, of a reciprocating linting-blade, substantially as and for the purposes set forth.

2. In a linting-machine, the combination, with a linting-blade, a slotted tube adjustably held to the frame of the machine, and means for holding said tube, said parts being arranged and adapted to operate substantially as and for the purposes set forth.

3. In a linting-machine, the combination, with a reciprocating linting-blade, of a slotted tube arranged in bearings in said machine and means for holding said bearings and allowing the tube to be changed in its relation to the blade, substantially as and for the purposes set forth.

4. In a linting-machine, the combination, with a slotted tube fixed in the frame of said machine, of a rocking frame and a blade carried by said rocking frame and having a reciprocating movement to and from said tube, and means for operating the rocking frame, substantially as and for the purposes set forth.

5. In a linting-machine, the combination, with fixed bearings $d' d'$, forming a slot between, of a linting-blade having a reciprocating movement to and from said slot, a feed-roller, a frame carrying the same, and means to actuate said roller and reciprocate said frame, substantially as and for the purposes set forth.

6. In a linting-machine, the combination, with fixed bearings $d' d'$ for the cloth, of a linting-blade free to enter between said bearings without impinging on said bearings, so as to allow of a free withdrawal of the cloth over said bearings and said blade, substantially as and for the purposes set forth.

7. In a linting-machine, the combination, with a linting-blade and bearings $d' d'$, of a reciprocating roll adapted to draw the lint fabric over said blade when the latter is in said slot, and means for operating said roll, substantially as and for the purposes set forth.

8. In a linting-machine, the combination,

with bearings $d' d'$, of a knife or blade g , adapted to enter between said bearings, said bearings having an enlarged chamber or opening d^2 behind the slot formed between said bearings, substantially as and for the purposes set forth.

9. In a linting-machine, the combination, with a bed-frame a , having bearings $d' d'$, with a slot between, of a rock-frame j , carrying a linting-blade, and means, as described, for operating said frame, and a rock-shaft t , roll-carrying arms $w w'$, and a feed-roll, and means, as described, for reciprocating said rock-shaft and feeding the cloth forward, substantially as set forth.

10. In a linting-machine, the combination, with the frame thereof, of a slotted tube adjustably held in its bearings $e e$, means for holding said tube in said bearings, the said bearings being adjustably held on said frame, and means for holding said bearings to said frame, substantially as and for the purposes set forth.

11. In a linting-machine, the combination, with a linting-blade and bearings $d' d'$, of a feed-roll 2, arranged on reciprocating arms or bearings, and means for reciprocating said arms, and a gear-wheel 4, worm-shaft 5, gear-wheel 7, ratched worm 8, and pawl 9, arranged on a fixture on said frame, substantially as and for the purposes set forth.

12. In a linting-machine, the combination, with a linting-blade and bearings $d' d'$, of a feed-roll, arms $w w'$, rock-shaft t , arm u , and a cam o , arranged and adapted to engage said arm u , and a spring 3 to reciprocate said feed-roll, substantially as and for the purposes set forth.

13. In a linting-machine, the combination, with a linting-blade and bearings $d' d'$, of rock-frame j , arm p , a feed-roll 2, arms $w w'$, rock-shaft t , having the projection u , and cams o and v , arranged on a driving-shaft q , substantially as and for the purposes set forth.

In testimony that I claim the foregoing I have hereunto set my hand this 15th day of October, 1888.

JAMES WAYLAND.
